UNITED STATES PATENT OFFICE.

CHARLES F. SALTER, OF KNOXVILLE, TENNESSEE, ASSIGNOR OF ONE-HALF TO H. C. HELM,
OF HARRIMAN, TENNESSEE.

GRATE FOR OPEN FIREPLACES.

No. 884,615.

Specification of Letters Patent.

Patented April 14, 1908.

Application filed November 26, 1907. Serial No. 403,906.

To all whom it may concern:

Be it known that I, CHARLES F. SALTER, a citizen of the United States, resident of Knoxville, in the county of Knox and State 5 of Tennessee, have made a certain new and useful Invention in Grates for Open Fire-places; and I declare the following to be a full, clear, and exact description of the same, such as will enable others skilled in the art to 10 which it appertains to make and use the invention, reference being had to the accompanying drawings, and to letters or figures of reference marked thereon, which form a part of this specification.

15 The invention relates to grates for open fire places and it consists in the novel construction and combinations of parts as hereinafter set forth.

In the accompanying drawings, illustrating the invention, Figure 1, is a perspective view of the grate basket; Fig. 2, is a section on the line 2—2, Fig. 3, showing dumping position of the grate in dotted lines; Fig. 3, is 20 a front view of the invention as applied; Fig. 25 4, is a similar view showing the summer front in position and the grate in dumping position; Fig. 5, is a detail perspective view showing one of the catch extensions; and Fig. 6, is a section on the line 6—6, Fig. 2.

30 The letter *a*, designates the grate basket having a front partly inclosed portion *a'*, open in rear, and having horizontal grate-bars *b*, the two outer bars *b'*, at each end being cast or joined together and provided 35 with laterally projecting pivots or trunnions *c*, located at about the center of gravity of the grate when filled with ashes and cinders and ready to be dumped, such pivots or trunnions being inset on a line with the end 40 surfaces of such end bars, a recess or notch *e*, being provided at each side of such trunnion in the grate bar at each end, such notch being open at top and bottom.

45 At each side of the front of the fire place is provided a strip *f*, having an inward projecting horizontal lug extension *g*, at right angles thereto, such lug extension having a deep notch or seat *g'*, therein, open at the top. Separated from this lug extension and 50 above the same each strip *f*, has a catch extension *h*, projecting at right angles thereto inward with relation to the fire place.

55 At the upper rear portion of the front portion *a'*, of the grate basket a catch seat or recess *i* open at its bottom, is provided at

each side, such seat or recess being guarded by a lip or tooth *j*, at the front thereof.

In the use of the invention the pivots or trunnions *c*, are seated in the notches *g'*, of the lug extensions *g*, such lug extensions being 60 received in the recesses *e*, of the end grate bars, whereby the proper location of such end grate bars at each side of the fire place is not interfered with. At the same time the grate basket is let down with the catch 65 seats *i*, thereof in engagement with the catch extensions *h*, and the guard lip or tooth *j*, in front of such catch extensions. Thus any tipping or turning of the grate upon its trunnions is prevented by the guard 70 lips *j* and the rear walls of the catch recesses *i*, abutting against the catch extensions *h*.

When it is desired to dump the grate it is lifted slightly, the trunnions rising in the open notches *g'*, and the guard lips or teeth 75 *j*, rising above the catch extensions *h*, when upon movement of the guard lips past the catch extensions and letting the grate down, the trunnions, which are still in place in the deep notches *g'*, will fall to their normal positions and the grate may be turned easily 80 upon the trunnions until it occupies the position shown in Fig. 4 of the drawings, wherein the horizontal grate bars are vertical and the vertically arranged front portion *a'*, of 85 the basket is horizontal with its open rear portion presenting downward. The weight of the grate, which is almost entirely in rear of the trunnions, will keep it in dumping position, and inasmuch as the trunnions and 90 their supports are all located within the fire place, a summer front, shown at *k*, may be readily placed and secured in position.

When it is desired to again use the grate it is only necessary to turn it forward upon its 95 trunnions and slightly lift it, so that the guard lips will pass the catch extensions as before stated, when, upon letting the grate down, said guard lips will maintain it in normal position.

100 Having described the invention, what I claim and desire to secure by Letters Patent is:

1. The combination with a fireplace having bearings at each side and a lateral projection above said bearings, of a grate provided with pivots engaging said bearings, and an upward extending front guard portion having detachable locking engagement with said lateral projection, said grate being adapted 105 110

to be lifted from said bearings to disengage it from said lateral projection.

2. The combination with a fireplace having bearings at each side and a lateral projection above said bearings, of a grate provided with pivots engaging said bearings, and an upward extending front guard portion having a catch recess open at its bottom and adapted to detachably engage said lateral projection

to lock the grate in position, said grate being adapted to be lifted from said bearings to disengage it from said lateral projection.

In testimony whereof I affix my signature, in presence of two witnesses.

CHAS. F. SALTER.
